INVENTOR.

LEWIS T. GARDNER
BY Victor J. Evans
ATTORNEY

UNITED STATES PATENT OFFICE.

LEWIS T. GARDNER, OF OAKLAND, CALIFORNIA.

PLATEN-PRESS GAUGE.

Application filed August 31, 1923. Serial No. 660,401.

To all whom it may concern:

Be it known that I, LEWIS TAYLOR GARDNER, a citizen of the United States, residing at Oakland, in the county of Alameda and 5 State of California, have invented new and useful Improvements in Platen-Press Gauges, of which the following is a specification.

This invention relates to improvements in 10 platen press gauges and has particular reference to a gauge adapted to be attached to the tympan paper of a printing press for the purpose of aligning a sheet of paper upon which an impression is to be made.

15 The principal object of this invention is to produce a gauge which is sturdy in construction, simple to manufacture and well within the purchase price of the average user.

20 A still further object is to produce a gauge which when positioned upon the tympan paper will not become displaced.

Another object is to provide means whereby it is impossible for the paper being fed 25 to the gauges to become caught in the same.

Another object is to provide an adjustable retaining finger which will maintain itself at all times in an adjusted position.

Other objects and advantages will be apparent during the course of the following 30 description.

In the accompanying drawings forming a part of this specification, and in which like numerals are employed to designate like 35 parts throughout the same,

Figure 1 is a fragmentary view of a tympan sheet having my gauges attached thereto and retaining a sheet to be printed,

Figure 2 is a vertical cross section of my 40 device in unlocked position,

Figure 3 is a vertical cross section of my device in a reversed position and locked to a tympan sheet,

Figure 4 is a side elevation of one of the 45 retaining fingers,

Figure 5 is a perspective view of the finger retaining block,

Figure 6 is a perspective view of the clamping member, and

50 Figure 7 is a perspective view of the clamping cam.

Many gauges have been devised, which gauges often failed to accomplish their pur-

pose through insufficient clamping and consequent slipping of the paper; they have 55 also, in many instances, failed through the fact that the paper being fed would become caught in the gauge and in many instances have been of such weak construction that they have been easily bent or crushed. 60

I have therefore sought to produce a gauge which is of sturdy construction, one which may be easily locked and one where it is impossible for the paper being fed to become 65 caught.

In the accompanying drawings wherein for the purpose of illustration is shown a preferred embodiment of my invention, the numeral 5 designates the tympan sheet and the numeral 6 the sheet of paper being fed 70 to the press, while at 7 I have shown a block having a dove-tail groove 8 formed in the upper surface thereof. This block has its rear portion provided with an over-hang 9, the purpose of which will be later seen. 75

A curved retaining finger 11 is adapted to be slidably held in the dove-tail groove 8 as shown in Figures 1, 2 and 3. The clamping member 12 is formed of a flat portion having an upturned end 13, and upturned side 80 pieces 14 and 16. These side pieces are each provided with a slot as shown at 17 and 18 for the reception of the reduced portions 19 and 21 of the clamping cam 22.

A pivot pin 23 serves to secure the block 85 7 to the clamping member 12 and at the same time the over-hang portion 9 of the block 7 serves to retain the clamping cam within the slots 17 and 18. An operating handle 24 formed integral with the cam 22 serves to 90 manipulate the same.

The pin 23 is provided with a head 26 (see Fig. 1). This head is adapted to lie between the side piece 16 and the operating lever 24. This arrangement prevents the 95 accidental removal of the pin and yet permits of a reversal of the operating lever as will be later shown.

In operation a slit is made in the tympan paper as shown at 27, through which the 100 curved end 13 of the clamping member 12 is placed. This brings the block 8 upon the top of the tympan paper and after the same has been moved to an adjusted position the lever 24 is moved from the position shown in Figure 2 to that shown in Figure 3 so as 105

to cause the cam 22 to abut the over-hang 8 and the rear end of the clamping member 12, thus efficiently clamping the portion of tympan paper between the block and 5 the clamping member.

By viewing Figure 3, it will be noted that the curved portion 13 causes the tympan paper to curve upward slightly with the result that any sheet fed will abut against the 10 end of the block 7 and cannot therefore become caught.

The finger 11 may now be adjusted by moving the same in the dove-tail slot in accordance with the wishes of the operator. 15 Should the operator desire to reverse the clamp so as to bring the operating lever upon the opposite side of the gauge he moves the lever to the vertical position of Figure 2, removes the pin 23 lifts the block 20 7 and reverses the position of the cam so that the operating lever will lie upon the opposite side of the clamping member. The parts are again replaced in such a manner that the head 26 of the pin 23 will be on the 25 side adjacent the operating lever.

It will thus be seen that I have provided a simple clamp and one which will accomplish all of the objects above set forth.

It is to be understood that the form of 30 my invention herewith shown and described is to be taken as a preferred example of the same, and that various changes in the shape, size and arrangement of parts may be resorted to without departing from the 35 spirit of the invention or the scope of the subjoined claims.

Having thus described my invention, I claim:—

1. In a gauge of the character described, a block, a dove-tail slot formed on the upper surface of said block, a clamping member pivoted to said block, a cam supported in said clamping plate, and means for moving said cam for the purpose of causing said clamping plate to move toward said block 40 throughout a greater portion of its length.

2. In a gauge of the character described, a block having a dove-tail slot formed in the upper surface thereof, a curved finger 50 slidable in the dove-tail slot, an over-hang formed on said block, a clamping plate pivoted to said block, a cam interposed between said clamping plate and said over-hang and means for operating said cam for the purpose of moving said clamping plate toward 55 said block through a greater portion of its length.

3. In a gauge of the character described, a block having a dove-tail slot formed in the upper surface thereof, a curved finger 60 slidable in the dove-tail slot, an over-hang formed on said block, a clamping plate pivoted to said block, a cam interposed between said clamping plate and said over-hang, means for operating said cam for the purpose of moving said clamping plate toward 65 said block through a greater portion of its length, said clamping plate having its forward end curved toward said finger.

In testimony whereof I affix my signature.

LEWIS T. GARDNER.
